DESIGN FOR A FOLDING FLOOR SCREEN

Seomon S. Lewis, New York, N. Y.

Application June 1, 1935, Serial No. 57,090

Term of patent 3½ years

To all whom it may concern:

Be it known that I, Seomon S. Lewis, a citizen of the United States, residing at New York city, in the county of New York and State of New York, have invented a new, original, and ornamental Design for a Folding Floor Screen, of which the following is a specification, reference being had to the accompanying drawing, forming a part thereof.

Fig. 1 is a front elevational view of a folding floor screen showing my new design.

Fig. 2 is a top plan view of the same.

Fig. 3 is a rear elevational view looking in the direction of the arrows of line 3—3 of Fig. 2.

Fig. 4 is a side elevational view looking in the direction of the arrows of line 4—4 of Fig. 2.

I claim:

The ornamental design for a folding floor screen as shown.

In testimony whereof I have affixed my signature.

SEMON S. LEWIS.
